FOLDABLE ASH TRAY

Canio Di Carlo, Jr., 159 Claremont Ave.,
Montclair, N.J. 07042

Filed Nov. 9, 1965, Ser. No. 88,056

Term of patent 14 years

(Cl. D85—2)

FIG. 1

FIG. 2

FIG. 3

FIG. 4

FIG. 5

FIG. 1 is a perspective view of a foldable ash tray showing my new design;

FIG. 2 is an edge elevational view;

FIG. 3 is a top plan view;

FIG. 4 is a transverse sectional view; and

FIG. 5 is an edge elevational view with the ash tray in folded condition.

I claim:

The ornamental design for a foldable ash tray, substantially as shown.
